UNITED STATES PATENT OFFICE.

JAMES D. DARLING, OF PHILADELPHIA, PENNSYLVANIA, ASSIGNOR TO HARRISON BROS. & CO., INCORPORATED, OF PHILADELPHIA, PENNSYLVANIA, A CORPORATION OF PENNSYLVANIA.

METHOD OF MAKING CYANIDS.

SPECIFICATION forming part of Letters Patent No. 698,463, dated April 29, 1902.

Application filed July 29, 1901. Serial No. 70,024. (No specimens.)

To all whom it may concern:

Be it known that I, JAMES D. DARLING, a citizen of the United States, residing at No. 4826 Greenway avenue, in the city and county 5 of Philadelphia and State of Pennsylvania, have invented a certain new and useful Improvement in the Manufacture of Alkaline Cyanids, of which the following is a specification, reference being had to the accompanying drawing.

There are many well-known processes by which the formation of alkaline cyanid is accomplished by the direct combination at proper temperatures of carbon, alkali, and 15 nitrogen. In most of these processes the alkali is supplied in the form of a hydrate or carbonate. In this case it is necessary to supply more carbon than is theoretically required, and as a result the product is a black 20 mass consisting of alkaline cyanid with a considerable excess of carbon, sometimes termed "cyanized" carbon. It is necessary in order to produce a marketable article to remove the carbon, which has usually been accomplished 25 either by converting the cyanized carbon into ferrocyanid or by filtration processes, which are tedious and expensive. In certain other processes the alkali is supplied in metallic form. In this case it is possible to convert 30 all of the carbon into alkaline cyanid; but the process is attended by the disadvantage of the comparatively high cost of the alkali metal. Furthermore, the nitrogen must then be supplied in the form of ammonia, which is much 35 more expensive than nitrogen by itself.

By my present invention I employ as the chief source of alkali the cheaper carbonate, hydroxid, or oxid, (preferably the latter,) and I get rid of the excess of carbon which would 40 remain if nothing else were used by subjecting the cyanized carbon thus produced to the action of alkali metal and ammonia-gas, whereby an additional quantity of alkaline cyanid is formed by the combination of this 45 excess of carbon with the alkali metal and ammonia-gas.

For carrying out my process no particular form of apparatus is necessary; but I prefer to employ one such as I have figured in the 50 accompanying drawing, in which—

A is a furnace having set within it large closed iron vessels B B. Two only are shown; but it is understood that any desired number may be employed. Each of these vessels contains an inlet-pipe C, reaching nearly to the 55 bottom, and an outlet-pipe D, leading from the top. The vessels are connected in series, as shown.

In my present process I introduce into each of the vessels an alkaline carbonate, hydroxid, 60 or oxid, and also carbon, which, as above explained, must be in excess. I also place in the bottom of the vessel a quantity of alkali metal which, in conjunction with the necessary amount of nitrogen, will be sufficient to 65 combine with the excess of carbon and produce a quantity of cyanid additional to that produced from the first-mentioned alkaline element. As soon as these materials have been brought to the proper temperature I 70 pass into the vessel at G a mixture of ammonia-gas and pure nitrogen, whereby two processes go on simultaneously. The nitrogen gas passes through the alkali metal without action and upon reaching the heated 75 carbon and alkaline carbonate, hydroxid, or oxid it combines therewith to form a cyanid. On the other hand, the ammonia-gas combines with the alkali metal and the remainder of the carbon, forming an additional quantity 80 of cyanid, the proportions of the ingredients being so supplied that as a result there remains in the vessel nothing but a mass of pure cyanid.

As an example of the proper proportions to 85 employ in this process I may take eighty pounds of caustic soda, twenty-three pounds of sodium, and sixty pounds of charcoal. Through these must be passed not less than twenty-eight pounds of nitrogen and seventeen pounds of ammonia-gas. As a result of the passage of the twenty-eight pounds of nitrogen through the caustic and charcoal there will be produced ninety-eight pounds 90 of alkaline cyanid, leaving twelve pounds of 95 carbon in excess, and as a result of the combination of this excess of carbon with the sodium and the nitrogen of the ammonia-gas there will be formed forty-nine pounds more of the alkaline cyanid, so that the result of 100

the entire process will be one hundred and forty-seven pounds of pure alkaline cyanid.

I have spoken of the ammonia and alkali metal as combining directly with the carbon.

5 It seems probable that there is formed intermediately an alkaline amid, which in turn combines with the carbon to form the cyanid. Consequently my process includes the use of an alkaline amid previously formed in place

10 of the corresponding amount of alkali metal and ammonia-gas. I prefer, however, as has been explained, to supply the metal and the ammonia as separate elements.

I have spoken of the nitrogen which is supplied for the purpose of combining with the carbon and the alkaline compound as being in its pure state. It is quite evident that it could be supplied in the form of ammonia, although it would be very uneconomical to 15 do so, owing to the increased expense. I desire, however, that it be understood that when

I speak of supplying nitrogen such supply may be either in the pure form or combined with other substances, and I desire it also to be understood that where in the claim I speak of an "alkaline oxid" I mean to include in said term alkaline hydroxids and carbonates, which are the equivalent thereof.

Having thus described my invention, I claim—

30 The process of producing pure alkaline cyanid, which consists in subjecting carbon and alkaline oxid to the action of nitrogen and simultaneously subjecting the excess of carbon to the action of alkali metal and ammonia, all under the influence of heat, substantially as described.

JAMES D. DARLING.
